Primary Examiner—Paula A. Mortimer

(57) **CLAIM**

The ornamental design for an aerosol container with actuator overcap, as shown and described.

DESCRIPTION

FIG. 1 is a perspective view of an aerosol container with actuator overcap showing our new design; FIG. 2 is a rear elevational view thereof; FIG. 3 is a side elevational view thereof; FIG. 4 is a front elevational view thereof; FIG. 5 is a top plan view thereof; and, FIG. 6 is a bottom plan view thereof. The broken lines in FIGS. 1, 2, and 6 are for illustrative purposes only and forms no part of the claimed design.
